INPUT CONTROLLER

Jens Morton, Philadelphia, Pa., assignor to Automatic Temperature Control Co., Inc., Philadelphia, Pa., a corporation of Pennsylvania

Application August 21, 1945, Serial No. 611,875

22 Claims. (Cl. 200—33)

1

This invention relates to input controllers, having particular reference to a device for regulating the relative times of power "on" and power "off" in the supply of current to an electric furnace.

There have been many devices for this purpose developed in the past, and many have been relatively satisfactory, but have possessed certain disadvantages, either in the matter of expense and complexity or in the necessity for the control of relatively small potentials, and in some cases the design has been such as to preclude the long life and freedom from necessary adjustments and replacements essential for such controlling systems.

It is among the objects of this invention: to provide an input controller of enhanced efficiency and long life; to obviate the disadvantages of prior art input controllers; to provide an input controller of efficiency and long life while being cheap and simple to construct; to provide an input controller of rugged construction capable of handling heavy potentials; to provide an input controller with a calibrated dial so arranged that the more frequently used part of the working dial is always in front of the operator instead of being concealed by the operator's hand as in earlier constructions; to provide an input controller by which the current flows without interruption when the instrument is set for 100% current input, despite timed rotation of the moving mechanisms; and other advantages will become more apparent as the description proceeds.

In carrying out the invention in a preferred instrument embodiment, a continuously driven timed shaft is provided driven by a timing motor and carrying a disc upon which a bell crank lever is mounted. A two-position rock member is pivoted to the instrument frame in operative relation at one end with circuit-making and breaking contacts. A slideable sleeve is mounted on the drive shaft and arranged for axial movement thereon movable normally in one direction by the bell crank lever, and movable in the other direction by the rock member in moving from one position of circuit-making to its other position of circuit-breaking. An adjustable tripping device is provided adjacent to the disc, carrying means for periodically moving the bell crank lever in adjustments angularly relative to the disc, for moving the sleeve in one direction to rock the rock element to open the circuit, and means are provided in predetermined fixed angular relation to the disc, driven by the shaft

2

for periodically rocking the member to open the circuit and move the sleeve axially to reset the bell crank. The tripping means in one given angular position engages an extension on the rock member to positively actuate the same to one rock position to establish and maintain a "made" circuit regardless of tripping actuations. Means are provided for preventing the tripping of the bell crank from actuating the sleeve to interrupt the circuit made in the one given angular position of the tripping means, and means are provided for varying the relative angular relation of the tripping means relative to the axis of the driven shaft.

15 In the accompanying drawings forming part of this description:

Fig. 1 represents a front elevation of the instrument according to a preferred embodiment, partially broken away, and showing the relative arrangement of dial and indicating pointer.

20 Fig. 2 represents a side elevation of the instrument, partially in section, in the housing therefor, shown in vertical section.

Fig. 3 represents a horizontal transverse section 25 of the instrument taken on line 3—3 of Fig. 2, showing the driven parts in one angular disposition and with the controlling sleeve pushed rearwardly on the drive shaft, and with the parts in circuit-breaking relation.

30 Fig. 4 represents a similar horizontal transverse section of the instrument, from the same view as the section comprising Fig. 3, showing the driven parts in a successive stage of angular disposition, and with the controlling sleeve pushed forwardly on the driving shaft, and with the parts in circuit-making relation.

35 Fig. 5 represents a partial vertical section of the instrument, taken on line 5—5 of Fig. 2, and showing the frictional device for holding the pointer in a set position.

40 Fig. 6 represents a partial section taken on line 6—6 of Fig. 3, showing in full lines the sleeve-actuating bell crank on the driven disc in the position to which it is moved by contact of its actuating dwell with the adjustably positioned roller controlled by the position of the pointer for the instrument, as it has reached its maximum position of inward movement under the 45 roller to move the sleeve toward circuit-opening position, and in dotted lines showing a successive angular position in which the actuating dwell has been returned to an operative position extending beyond the periphery of the disc, 50 after the associated bell crank has been moved

into a position in which the sleeve has moved to circuit-making position.

Fig. 7 represents a partial section taken on line 7-7 of Fig. 4, showing the rock member and sliding sleeve connection.

Fig. 8 represents a fragmentary section taken on line 8-8 of Fig. 7, showing in full lines a position of resetting cam and the lug on the rock member, at the instant that the rock element has been moved to close the circuit, and in dotted lines the relative positions of the parts during circuit opening.

Fig. 9 represents a fragmentary section taken on line 9-9 of Fig. 2, showing the circuit-making and breaking means.

Fig. 10 represents a fragmentary section showing the relation of the rocking member to the cam slope on the adjustable tripping member, when the tripping member is positively moved to retain the "made" circuit.

Referring to Fig. 1, the front of the instrument assembly is shown, comprising a housing of conventional form 10 in which the instrument 11 is mounted. The instrument has a front panel 12 disposed behind the apertured front face 19 of the housing 10, and on which there is mounted the circular dial 13 calibrated for convenience into units of 5 from "zero" at "100" at the lower center of the dial, through equal angular divisions and sub-divisions as at 14, to "100," representing percentages of time. A manual control knob 15 extends through the dial 13, and controls the angular position of a pointer 16 sweeping the calibrations 14 and mounted on the control shaft, to be described. A supporting panel 17 is shown, upon which an insulating terminal block 18 is mounted, carrying preferably two sets of pairs of binding posts or terminals and buss bars. Illustratively, a pair of power connectors are shown joined to the lower terminals 20 and 21 on the respective buss bars 22 and 23, from which the current is supplied for running the timing motor 48, to be described, and which is lead to and from the motor through terminals 24 and 25 respectively on the respective buss bars 22 and 23. In laterally spaced relation, and well insulated therefrom, are the furnace circuit buss bars 26 and 27, carrying the lower terminals 28 and 30 respectively, to which leads extend to a furnace or to a supplemental controlling system or relay, while the upper terminals thereof, respectively 31 and 32, extend into the instrument for electrical connection to the circuit controlling contacts, to be described. A stop pin 29 is preferably provided at the lower center of the dial between graduation No. 1 and No. 100, against which the pointer 16 controlled by the knob abuts at the calibration 14 designated as point "100," on one side thereof, while abutting the pin adjacent graduation No. 1, on the other, depending upon whether the instrument is set for substantially "no" percentage of input, or of "100%" thereof, and this latter is coincident with the calibration 14 identified on the dial as "100." It will be observed that the 50% calibration 14 is at the top of the dial, and as most of the adjustments are within a reasonable range of this point, during the actual running of the instrument after starting, this is very easily accomplished without the adjustment being interfered with visually by the hand of the operator grasping the knob 15.

Referring to Figs. 2, 3 and 4, it will be observed that the knob 15 is anchored to a control shaft 33 journalled in the front panel 12 and extending through the center of the dial and the housing

glass or other transparent cover 39 supported thereby, and the indicating pointer 16 is keyed to the shaft 33. The latter is enlarged inwardly of the front panel 12 into an enlarged head 34.

- 5 The enlarged head 34 has a peripheral groove 35 on its outer periphery into which resilient wires 36 extend, arranged to bear laterally against the groove to impart a frictional drag thereto to hold the shaft wherever it is manually set by knob 15.
- 10 The drag wires 36 are anchored suitably to the inner surface of the front panel as at 37. The head enlargement 34 of the shaft 33 is axially apertured on its rearward face concentric with shaft 33 in a bearing recess 40 to receive and journal the forward end of a continuously driven shaft 41, the axis of which is coincident with that of shaft 33. Shaft 41, as will be explained, extends perpendicularly between the front and rear panels of the instrument. Mounted rigidly on the rear face of the head enlargement 34, and extending radially thereof, to turn in a plane normal to the shaft 33, is a tripping arm 42, having a predetermined and fixed angular divergence, behind the dial and front panel 12, from the radial dis-
- 15 position of the indicating pointer 16 in front of the dial. Illustratively, this angular divergence is 90°, although this is purely for convenience and any other angular relation can be used. The outer free end of the tripping lever 42 is formed with a diagonal cam slope 49, below the peak of which a perpendicular pin 43 is provided, parallel to the axis of the shaft 33. The pin 43 carries rotatable anti-friction roller sleeve 44 comprising the primary tripping member of the arm 42. The cam slope 49 comprises a secondary tripping member.

The continuously driven shaft 41 at the rear end extends through and is journalled in the rear panel 59, and carries in rear of the rear panel 59 a gear 45 splined to the shaft 41, in mesh with a pinion gear 46 keyed on the output shaft 50' of a gear reduction 50, mounted inwardly of the rear panel. The gear reduction 50 is in driven relation to the armature of a preferably synchronous uni-directional constant speed motor 48. The shaft 41 is constantly driven at a carefully timed rate by the motor, and illustratively, it makes one complete rotation in sixty seconds. Toward the forward end the shaft 41 carries a driven annular disc 51, keyed suitably to the shaft, and disposed closely adjacent to but in parallel spaced relation relative to the tripping arm 42, and so disposed that part at least of the roller 44 overhangs rearwardly beyond the periphery of the disc. The disc 51 is of such diameter as to have close but non-contacting relation to and slight clearance from the roller 44 of the primary tripping element. The disc 51 has a pair of lateral ears struck rearwardly out of its surface adjacent to the outer periphery thereof, and extending perpendicularly of the disc as at 53 and 54, which form journals for a pivot pin 55. The pin 55 is disposed parallel to the disc with its axis substantially tangential to the axis of the shaft 41, in order to carry a sleeve-actuating member, to be described. Axis pin 55 and its associated assembly is counterweighted substantially diametrically of the disc by counterweight 52.

A bell crank lever is carried by disc 51, journalled to the pivot shaft 55 by suitable ears 57 and 58 extending from a short arm 60 of the bell crank lever. Short arm 60 extends generally perpendicularly relative to the disc 51, and has a narrow reduced terminal portion 61, extending forwardly 75 of the instrument through an aperture 62 formed

in the disc 51, in which it has a limited working substantially radially of the disc. The bell crank lever on the other side of the pivot 55 extends angularly from short arm 60 in a flat plate 63 generally perpendicular to the short arm 60, and extending toward the shaft 41. The flat portion is apertured adjacent to the pivot pin 55, as at 64, and in substantial longitudinal alignment therewith carries a lateral stud 65. A plate 66 is provided arranged to overlie and engage in parallelism the flat portion 63 of the bell crank lever, and includes at one end a laterally projecting lug or ear 69 extending into the aperture 64, as a free pivot for the plate relative to the bell crank lever flat portion 63. The plate has an elongated slot 67 in which the stud 65 extends, and the outer end of the stud carries a resilient unit 68 to resiliently but yieldingly urge the plate into parallelism against and in substantial alignment with the flat part of the bell crank, while yieldingly permitting relative angular displacements thereof of about the pivot formed of the lug 69 in aperture 64, in the event of resistance to joint movement of the bell crank and plate in aligned relation. The inward lower end of the flat plate 66 terminates in spaced fingers 70 and 71 extending inwardly respectively radially of the axis of the driven shaft 41. For actuating the bell crank by forcing the free end 61 inwardly radially of the disc 51, a member is provided on the disc, comprising a pivotally slidable actuating member 72 pivoted to the disc 51 toward one end as at 73, and disposed in parallel sliding relation to and on the disc 51. The member 72 has a bell crank arm 74 arranged to abut the ear 53 to limit the outward movement of the member 72 on its pivot 73, and is held for limited inward motion, as well as guidably against movement away from the disc, by a struck-out ear 75 parallel to the disc 51. The member 72 carries outwardly a pointed dwell 76, arranged to move with the member outwardly to a position extending beyond the periphery of the disc 51, from a position not so projected but substantially flush with the disc periphery. The actuating member also carries an inwardly directed pointed extension 77 arranged to rest upon and transmit thrust to the small end of the bell crank 61, as the outwardly directed dwell 76 is forced inwardly with the member by the roller 44 of the primary tripping element, as they relatively contact in the rotations of the disc relative to the variably positioned tripping arm. Conversely, an opposite movement of the bell crank lever on its pivot pin 55 raising lever end 61, resets the actuating member with pointed dwell 76 extending beyond the periphery of the disc ready for the next contact with tripping roller 44 in the cyclic rotation of disc 51.

A sliding sleeve 78 is mounted loosely on the drive shaft 41, arranged for limited axial motion on the shaft, and is preferably formed of an insulating plastic material. The sleeve has a pair of recesses, or an annular groove 80 toward the front end of the sleeve, and the radial fingers 70 and 71 associated with the bell crank frictionally engage in groove 80 to positively move the sleeve axially in one direction with and through actuation of the bell crank lever and flat plate connections, whenever the point dwell 76 of the actuating member 72 is forced inwardly by engagement thereof by the primary tripping roller 44. This happens wherever primary tripping member 44 may be located by the controlled disposition thereof by the angular setting of the pointer or

indicator 16, through manipulations of the knob 15, with one important exception. This is at the instant angular setting associated with registration of the pointer 16 with calibration 14 identified as "100" abutting the stop 29, when, as will be explained, the contacts and associated parts, including the sleeve are locked in circuit-making relation. In the periodic energization of the bell crank during this angular setting of the tripping arm, relative angular lateral flexing of the bell crank and flat plate can occur, by utilizing the resilience of the resilient assembly 68.

The front and rear panels are connected by spaced pillars 31, as is usual in such instruments, 15 and between an adjacent pair of pillars 81, a transverse shaft 82 is mounted, the axis of which is substantially tangential to the axis of the driven shaft 41, and which shaft is disposed substantially medially between and parallel to the respective front and rear panels. A rock element 83 is journaled on the shaft 82 for oscillation in the substantial center of the instrument, and at one side of the pivot shaft carries an angularly divergent inwardly extending arm 84, terminating 20 in a yoke including a pair of radially extending fingers 85 and 86, which engage in recesses or a groove 87 formed on the rear end of the sliding sleeve 78. The arm 84 adjacent the fingers is formed with a rearwardly struck out sloping ear 88, the front edge 89 of which at the end of its slope is, illustratively, preferably parallel to the arm 84. The arm 84 and the rock element 83 and the sleeve 78 are moved rearwardly by the rearward sliding of the sleeve 78, in response to 25 inward actuation of the bell crank lever arm 61 cyclically in the rotation of the shaft and disc. A hub 90 is keyed to the shaft 41 and carries a radially extending arm 91, carrying a cam slope 92, arranged to engage the struck-out lug 88 on the arm 84, to rock the shaft forwardly and simultaneously to force the sleeve 78 forwardly. As noted, forward movement of the sleeve resets 30 the actuating member and bell crank lever.

The rock member 83 at the forward end adjacent to the front panel is twisted or shaped to form a tripping end 93, juxtaposed to the plane and path of motion of the tripping arm 42, overlying and in position to be engaged and the forward end of the rock element raised, by the sloping cam surface 49 on the tripping arm in order to lock the contacts, to be described, in circuit-closing engagement as the indicator pointer 16 is moved to the "100%" indication. At the rearward end the rock member is sharpened as at 94, and is arranged to engage in one position the upper surface of a stop or detent stud 95 mounted on a spring arm 97 mounted on and generally parallel to the rear panel 69, which stud is of generally rounded contour having a frictional engagement with the sharpened end of the rock member to retain the rock member in a given raised or lowered position until positively moved by the mechanism previously discussed. A second stud 96 is provided spaced from the first as 45 to form a stop recess in which the end of the rock member is frictionally held in an inward, circuit-closing position.

Mounted on the rear panel, in insulated relation thereto, is the rigid bracket arm 100 carrying toward its free end a guide cylinder 101 in which a plunger 102 is guided in position to be engaged and depressed by the end of the rock member adjacent to the sharpened end thereof. A resilient contact-making arm 104 is mounted 50 on the under side of the bracket arm 100 in po-

sition to be flexed downwardly away from the bracket arm 100. The resilient arm 104 carries a contact 105, in position to engage and establish a circuit with a yielding contact 106 carried on a resilient arm 109 mounted below a relatively rigid bracket 107, when depressed by the plunger 102. The working circuits are connected to terminals for the respective contact-making arms, as will be understood.

The instrument in use is suitably wired to the motor-driving circuits by means of the terminals 20 and 21, and the motor 48 is then continuously driven in a timed output of the illustrative sixty seconds of drive shaft 44. The relay or electronic or other furnace control system is wired to the respective terminals 28 and 30 of the instrument, and the instrument is ready for its timing function. It will be understood, of course, that the leads from the upper terminals 24 and 25, and 31 and 32, will already have been properly established in the instrument. Assuming a cold furnace which is to be brought up to heat in the shortest interval possible, the control knob 15 will be turned angularly toward bringing the pointer 16 against the pin 29, in which it will overlie the "100%" calibration 14. This swings the internally disposed tripping lever 42 to a position relative to the overhanging end 93 of the rock member 83, to be engaged by some lower portion of the cam slope 49 of the tripping lever, and continuation of the knob rotation to attain the "100%" setting forces the end 93 of the rock member upwardly on the cam slope 49 until the sharpened end 94 rides over the spring pressed detent 95 to a position between detents 95 and 96, and thus forces the plunger 102 downwardly to force the flexible contact member 104 downwardly to establish circuit-making engagement between the contact points 105 and 106. The latter are in connection respectively with the terminals 31 and 32, and control the working circuit. The circuit-making arrangement is maintained during the time that the tripping lever is engaged with the end 93 of the rock member 83. However, during this entire interval, regardless of its duration, and which is controlled by the operator who keeps track of the furnace temperature, or who by experience knows the length of time of full 100% input necessary to attain the desired temperature. As the raising of the end 93 of the rock member 83, through the engagement thereof by the cam slope forces the arm 84 toward the front of the instrument, the sleeve 78 is also moved forwardly to the position it always assumes during the "making" of the circuit. As the drive shaft 44 rotates and the disc 51 rotates with it, the radially projecting cam dwell 76 on the actuating slide lever engages and is forced inwardly by the roller 44 of the primary tripping means on arm 42, and rides thereunder by being pushed radially inwardly until below the roller, which will be approximately at the peripheral edge of the disc. This forces the inner point 77 thereof substantially radially against the narrow end 61 of the bell crank lever and forces the latter to swing on its pivot 55. As at this juncture, however, the sleeve 78 is held forwardly, the flat plate 66 connected by its fingers 76 and 78 in the groove 80 is held at the lower end against movement with the bell crank lever, and the plate simply assumes a position of relative angularity to the flat end of the bell crank lever, through the resilient and pivotal connections between the parts. In the cyclic rotation of the drive shaft the driven arm 91 car-

rying the cam slope 92 passes across the front of, but without moving or actually contacting the struck-out lug 88 of the arm 84 of the rock member, as the latter arm has been previously 5 swung with the rock member 83 to the circuit-making position in which the arm 84 moves forwardly with the sleeve 78 to which it is pivotally connected.

Assume now that the furnace has reached the 10 desired temperature and it is desired to modify the input to maintain the attained temperature of the furnace. The operation, to be described, will pertain to any situation in which proportionality of "on" and "off" is desired within the time 15 cycle of the instrument, whether it be a high relative proportion of power input to the furnace, attendant, for instance, upon the placing therein of cold work, or a low relative proportion of power on, attendant, for instance, upon the removal of heated work, or for any other control 20 purposes that may arise. Let it be assumed for pure example, that it is desired to divide the cycle into two equal periods in the complete cycle, of which one is power "on" and the other is power "off." This is represented by the disposition 25 of the pointer 16 in overlying relation to the calibration 14 representing "50%" at the top of the dial. The tripping lever 42 will be backed away from its previous position in raising contact 30 with the end 93 of the rock member 83, which will for a short interval, possibly, remain where it was, depending upon the instant angular disposition of the parts driven by shaft 44, with the sharp end 94 disposed between the frictional retaining studs 95 and 96, and with the plunger 102 still depressed and the contacts in engagement. In due course, the elevated point dwell 35 of the actuating element will engage and ride under the roller 44 of the primary tripping element and the bell crank lever will be actuated as before, but this time, as the sleeve is not held against axial sliding except by its own negligible friction, and that offered by the associated parts, including that offered by the rounded stud 95 to 40 the passage of the sharpened end 94 of the rock shaft, which latter is a function of the resilience of the spring arm carrying the studs 95 and 96, the lower plate 66 of the bell crank lever will force the sleeve 78 rearwardly, thus moving the 45 arm 84 rearwardly, and rocking the rock member 83 so that the end 94 slides over the stud 95 to a disposition just above it. This releases the pressure on the plunger 102 and the spring contact arm 104 follows the plunger upwardly to separate 50 the contacts and break the circuit. After thirty seconds of rotation of the drive shaft 44, the cam slope 92 on the arm 91 engages the struck-out lug 88 on the arm 84, forcing it forwardly, and thus forcing the sleeve 78 forwardly to reset the bell crank lever for its next actuation by the primary trip element, and also moves the rock member 55 so that the sharpened end slides over stud 95 to retained position between studs 95 and 96 while, of course, actuating the plunger 102 to 60 close the circuit through the contacts. This established circuit maintains for thirty seconds when it is again interrupted by the cam slope on the driven arm 91, and the circuit is "made" for 65 another thirty seconds, and so on.

The relative times "on" and "off" can be proportioned by suitably positioning the indicator pointer 16 from "1%" or a fraction thereof, to the full "100%", and the disposition of the dial with the median portion upwardly facilitates the easy adjustment of the pointer in the more com-

monly used range of from perhaps 20% to 80% of input.

The simplicity, ruggedness and the advantages of the instrument are thought to be obvious.

Having thus described my invention, I claim:

1. In timers for controlling an electric circuit, a driven member, a single circuit-controlling switch as the sole circuit-controlling element of the timer, switch-operating means movable between two positions corresponding respectively to make and break of the circuit controlled by the timer, means driven by the member for moving the operating means to one of its said positions once during a complete movement of the driven member, a second means driven by the member for moving the operating means to the other of its said positions once during a complete movement of the driven member, and means manually settable during movement of said member for varying the time interval between the respective movements of the switch-operating means.

2. In timers for controlling an electric circuit, a driven member, a single circuit-controlling switch as the sole circuit-controlling element of the timer, switch-operating means movable between two positions corresponding respectively to make and break of the circuit controlled by the timer, means driven by the member for moving the operating means to one of its said positions once during a complete movement of the driven member, a second means driven by the member for moving the operating means to the other of its said positions once during a complete movement of the driven member, means manually settable during movement of said member for varying the time interval between the respective movements of the switch-operating means, the manually settable means including an element for moving the switch-operating means to one of its two positions and for nullifying the action of the respective moving means driven by the member during a complete member movement.

3. In timers for controlling an electric circuit, a driven member, a single circuit-controlling switch as the sole circuit-controlling element of the timer, switch-operating means movable between two positions corresponding respectively to make and break of the circuit controlled by the timer, means driven by the member for moving the operating means to one of its said positions once during a complete movement of the driven member, a second means driven by the member for moving the operating means to the other of its said positions once during a complete movement of the driven member, and means manually settable during movement of said member for varying the time interval between the respective movements of the switch-operating means, said driven member comprising a continuously rotated shaft.

4. In timers for controlling an electric circuit, a driven member, a single circuit-controlling switch as the sole circuit-controlling element of the timer, switch-operating means movable between two positions corresponding respectively to make and break of the circuit controlled by the timer, means driven by the member for moving the operating means to one of its said positions once during a complete movement of the driven member, a second means driven by the member for moving the operating means to the other of its said positions once during a complete movement of the driven member, means

manually settable during movement of said member for varying the time interval between the respective movements of the switch-operating means, said member comprising a continuously rotated shaft, and said switch-operating means comprising a reciprocable element operatively associated with both of said moving means driven by the shaft.

5. In timers for controlling an electric circuit, a driven member, a single circuit-controlling switch as the sole circuit-controlling element of the timer, switch-operating means movable between two positions corresponding respectively to make and break of the circuit controlled by the timer, means driven by the member for moving the operating means to one of its said positions once during a complete movement of the driven member, a second means driven by the member for moving the operating means to the other of its said positions once during a complete movement of the driven member, means manually settable during movement of said member for varying the time interval between the respective movements of the switch-operating means, said member comprising a continuously rotated shaft, and said switch-operating means comprising a sleeve mounted on the shaft and arranged for axial movements thereon.

6. In timers, a driven member, a circuit-controlling switch, switch-operating means movable between two positions corresponding respectively to make and break of the circuit controlled by said switch, means driven by the member for moving the operating means to one of its said positions once during a complete movement of the driven member, a second means driven by the member for moving the operating means to the other of its said positions once during a complete movement of the driven member, means manually settable during movement of said member for varying the time interval between the respective movements of the switch-operating means, said manually settable means comprising an arm, a stop on said arm, and means for rotating the arm about an axis to position the stop adjustably relative to the path of travel of one of said member driven means, and said last mentioned member driven means being arranged for operation by effective contact with said stop.

7. In timers, a continuously driven rotatable shaft, a circuit-controlling switch, switch-operating means comprising a compound lever having a plurality of arms and pivoted for movement so that each arm has two positions and one is operatively associated with the switch and corresponds in its two positions to circuit "on" and circuit "off" of the switch, means driven by the shaft for actuating one of the arms of the switch-operating means to urge said one arm to one of its two positions once during a complete rotation of the shaft, a second means driven by the shaft for actuating one of the arms of the switch-operating means to urge said one arm to the other of its two positions once during a complete rotation of the shaft, and means manually settable to predetermine the point of angular movement of one of said driven means at which it is actuated to actuate the arm of the switch-operating means relative to the angular point of operation of the other of said driven means to vary the proportionate time of circuit "on" to circuit "off" of said switch.

8. In timers, a continuously driven rotatable shaft, a circuit-controlling switch, switch-operating means comprising a compound lever having

a plurality of arms and pivoted for movement so that each arm has two positions and one is operatively associated with the switch and corresponds in its two positions to circuit "on" and circuit "off" of the switch, means driven by the shaft for actuating one of the arms of the switch-operating means to urge said one arm to one of its two positions once during a complete rotation of the shaft, a second means driven by the shaft for actuating one of the arms of the switch-operating means to urge said one arm to the other of its two positions once during a complete rotation of the shaft, means manually settable to predetermine the point of angular movement of one of said driven means at which it is actuated to actuate the arm of the switch-operating means relative to the angular point of operation of the other of said driven means to vary the proportionate time of circuit "on" and circuit "off" of said switch, and manual means operative to engage one of said arms to move the switch-operating means positively to and to maintain it in one of its said positions despite the continued actuation of the driven means with the rotation of the shaft.

9. In timers, a continuously driven rotatable shaft, a circuit-controlling switch, switch-operating means comprising a compound lever having a plurality of arms and pivoted for movement so that each arm has two positions and one is operatively associated with the switch and corresponds in its two positions to circuit "on" and circuit "off" of the switch, means driven by the shaft for actuating one of the arms of the switch-operating means to urge said one arm to one of its two positions once during a complete rotation of the shaft, a second means driven by the shaft for actuating one of the arms of the switch-operating means to urge said one arm to the other of its two positions once during a complete rotation of the shaft, means manually settable to predetermine the point of angular movement of one of said driven means at which it is actuated to actuate the arm of the switch-operating means relative to the angular point of operation of the other of said driven means to vary the proportionate time of circuit "on" and circuit "off" of said switch, said manual means including a cam operative to engage one of said arms to move and maintain the switch-operating means in one of its said positions despite the continued rotation of the respective driven means.

10. In timers, a continuously driven rotatable shaft, a circuit-controlling switch, switch-operating means comprising a compound lever having a plurality of arms and pivoted for movement so that each arm has two positions and one is operatively associated with the switch and corresponds in its two positions to circuit "on" and circuit "off" of the switch, means driven by the shaft for actuating one of the arms of the switch-operating means to urge said one arm to one of its two positions once during a complete rotation of the shaft, a second means driven by the shaft for actuating one of the arms of the switch-operating means to urge said one arm to the other of its two positions once during a complete rotation of the shaft, and means manually settable to predetermine the point of angular movement of one of said driven means at which it is actuated to actuate the arm of the switch-operating means relative to the angular point of operation of the other of said driven means to vary the proportionate time of circuit "on" to circuit "off" of said switch, the setting of one

5 shaft driven actuating means for actuation of the said arm of the switch-operating means being accomplished by the actuation of the other of said driven members and vice versa, in serial order during the rotation of the shaft.

11. In timers, a continuously driven rotatable shaft, a circuit-controlling switch, switch-operating means comprising a compound lever having a plurality of arms and pivoted for movement so that each arm has two positions and one is operatively associated with the switch and corresponds in its two positions to circuit "on" and circuit "off" of the switch, means driven by the shaft for actuating one of the arms of the switch-operating means to urge said one arm to one of its two positions once during a complete rotation of the shaft, a second means driven by the shaft for actuating one of the arms of the switch-operating means to urge said one arm to the other of its two positions once during a complete rotation of the shaft, means manually settable to predetermine the point of angular movement of one of said driven means at which it is actuated to actuate the arm of the switch-operating means 15 relative to the angular point of operation of the other of said driven means to vary the proportionate time of circuit "on" to circuit "off" of said switch, and a sleeve mounted on the shaft and engaging an arm of said switch-operating means and one of said shaft driven members.

12. In timers, a driven shaft, means for driving the shaft at a predetermined speed, a circuit controlling switch, switch operating means comprising a compound lever having a plurality of arms, means pivoting the lever for rocking movement between two positions, one of said arms being operatively associated with the switch to control the "on" and "off" settings thereof in accordance with the respective positions of the 20 lever, means driven by the shaft for moving the lever between its two positions in variably timed intervals, and a resilient detent bearing against the one of said arms to hold it in each of its attained two positions.

13. In timers, a driven shaft, means for driving the shaft at a predetermined constant speed, a circuit controlling switch, a compound lever having a plurality of arms, means pivoting the lever for rocking movements between two positions, one of said arms being operatively associated with the switch to control the "off" and "on" settings thereof in accordance with the respective positions of the lever, spring detent means urging the lever to remain in its respective positions, 25 means driven by the shaft for moving the lever on its pivot at variably timed intervals against the resilience of the detent means.

14. In timers, a driven shaft, means for driving the shaft at a predetermined constant speed, a circuit controlling switch, a compound lever having a plurality of arms, means pivoting the lever for rocking movements between two positions, one of said arms being operatively associated with the switch to control the "off" and "on" settings thereof in accordance with the respective positions of the lever, means driven by the shaft for moving the lever on its pivot at variably timed intervals, said means comprising two elements mounted on and driven by the shaft, means operated by one element for moving the lever in one direction, means operated by the other of the two elements for moving the lever in the other direction, and means for varying the interval between the operation of the last two mentioned means.

15. In timers, a driven shaft, means for driving the shaft at a predetermined constant speed, a circuit controlling switch, a compound lever having a plurality of arms, means pivoting the lever for rocking movements between two positions, one of said arms being operatively associated with the switch to control the "off" and "on" settings thereof in accordance with the respective positions of the lever, means driven by the shaft for moving the lever on its pivot at variably timed intervals, said means comprising two elements mounted on and driven by the shaft, means operated by one element for moving the lever in one direction, means operated by the other of the two elements for moving the lever in the other direction, and means for varying the interval between the operation of the last two mentioned means, said varying means comprising a manually settable lever and means on the lever for operating one of the said two operating means.

16. In timers, a circuit controlling switch, a driven rotatable shaft, means for driving the shaft at a constant predetermined speed, a pair of elements mounted on the shaft in axially spaced relation, a sleeve slidably mounted on the shaft between the elements, said elements having operating means in substantial axial alignment longitudinally of the shaft, switch controlling means operatively associated with each switch and operated in one direction by one of said operating means on its said element in one angular position of the shaft, said switch controlling means being coupled to the sleeve to move same axially, said operating means on the other of the said elements being coupled to and movable with the sleeve, and manually settable means movable angularly of the shaft from a position in substantial longitudinal alignment with the respective operating means to any desired angular position and disposed as to actuate the operating means of said other element at a predetermined angular position of said shaft angularly spaced from one angular position to move the sleeve and switch controlling means.

17. In timers, a circuit controlling switch, a pivoted lever having arms and arranged to operate the switch between "on" and "off," a rotatably driven shaft, means for driving the shaft at a constant speed, a manual control shaft substantially coaxial with the driven shaft, a tripping lever mounted on the manual control shaft and rotatable therewith through substantially 360°, a supporting element mounted on and rotatable with the driven shaft in juxtaposition to the tripping lever, a bell crank lever pivoted on the supporting element on a pivot substantially tangential to the driven shaft, means on the tripping element for moving the bell crank on its pivot so that one end thereof moves substantially axially of the driven shaft whenever in its rotation with the driven shaft the bell crank is actuated, a sleeve slidably mounted on the driven shaft, means connecting the sleeve and the bell crank to cause them normally to move together, one of the arms of said pivoted lever being connected to said sleeve to move with the sleeve, a second supporting element mounted on and rotatable with the driven shaft axially spaced from the first mentioned supporting element, means on the second supporting element for moving the pivoted lever at a predetermined angular position of the driven shaft as it rotates and thus to axially move the sleeve and also to move the switch to one of its conditions of "on" or "off," the tripping means being angularly settable to

vary the interval of angular motion of the driven shaft after the sleeve movement from the means of the second mentioned supporting element has been accomplished to establish the time interval at which the bell crank lever is actuated to urge the sleeve in the other direction to reverse the direction of the switch.

18. In timers, a circuit controlling switch, a pivoted lever having arms and arranged to operate the switch between "on" and "off," a rotatably driven shaft, means for driving the shaft at a constant speed, a manual control shaft substantially coaxial with the driven shaft, a tripping lever mounted on the manual control shaft and rotatable therewith through substantially 360°, a supporting element mounted on and rotatable with the driven shaft in juxtaposition to the tripping lever, a bell crank lever pivoted on the supporting element on a pivot substantially tangential to the driven shaft, means on the tripping element for moving the bell crank on its pivot so that one end thereof moves substantially axially of the driven shaft whenever in its rotation with the driven shaft the bell crank is actuated, a sleeve slidably mounted on the driven shaft, means connecting the sleeve and the bell crank to cause them normally to move together, one of the arms of said pivoted lever being connected to said sleeve to move with the sleeve, a second supporting element mounted on and rotatable with the driven shaft axially spaced from the first mentioned supporting element, means on the second supporting element for moving the pivoted lever at a predetermined angular position of the driven shaft as it rotates and thus to axially move the sleeve and also to move the switch to one of its conditions of "on" or "off," the tripping means being angularly settable to vary the interval of angular motion of the driven shaft after the sleeve movement from the means of the second mentioned supporting element has been accomplished to establish the time interval at which the bell crank lever is actuated to urge the sleeve in the other direction to reverse the direction of the switch, and means on said tripping lever arranged to directly engage an arm of said pivoted lever in one angular setting of the tripping means to positively move the pivoted lever to establish and maintain a given switch setting, and means responsive to the attainment of such last mentioned maintained switch setting to nullify the operations of both of the means of the respective supporting elements on said shafts.

19. In timers, a dial calibrated from zero to one hundred, means mounting the dial with the intermediate portions of the calibrations at the upper portion, a knob and pointer operative relative to the dial, and time controlled circuit controlling means operatively associated with the pointer for establishing and breaking a given circuit in variably timed intervals each proportional to the relative percentage indicated by the juxtaposition of the pointer and dial.

20. In timers for controlling an electric circuit, a rotatably driven member, a single circuit-controlling switch as the sole circuit-controlling element of the timer, switch operating means movable between two positions corresponding respectively to make and break of the circuit, means in fixed angular relation to the driven member driven by the member for moving the operating means to one of its said positions once during a complete rotation of the driven member, a second means in a fixed angular relation

to the driven member and to the first mentioned means of fixed angular relation driven by the member for moving the operating means to the other of its said positions once during a complete rotation of the driven member, a selected one of said means of fixed angular relation comprising a tripping element responsive to impingement upon a tripping abutment in instantaneously fixed tripping relation to and lying in the rotative path of movement of said selected means with the driven member, a tripping abutment, and manual means for angularly moving the tripping abutment for positioning said tripping abutment in a desired angular position on said path for variably predetermining the time interval between the respective movements of the switch-operating means.

21. In timers for controlling an electric circuit, a rotatably driven member, a single circuit-controlling switch as the sole circuit-controlling element of the timer, switch operating means movable between two positions corresponding respectively to make and break of the circuit, means in fixed angular relation to the driven member driven by the member for moving the operating means to one of its said positions once during a complete rotation of the driven member, a second means in a fixed angular relation to the driven member and to the first mentioned means of fixed angular relation driven by the member for moving the operating means to the other of its said positions once during a complete rotation of the driven member, a selected one of said means of fixed angular relation comprising a tripping element responsive to impingement upon a tripping abutment in instantaneously fixed tripping relation to and lying in the rotative path of movement of said selected means with the driven member, a tripping abutment, manual means for angularly moving the tripping abutment for positioning said tripping abutment in a desired angular position on said path for

5 variably predetermining the time interval between the respective movements of the switch operating means, said switch operating means comprising a movable lever having a portion juxtaposed to said path and arranged in its movement to move said portion relative to said path, and means operatively associated with the manual means for engaging said portion to move it relatively to said path to hold said lever in a 10 predetermined position at which the switch circuit is closed.

22. In timers, a cyclically movable driven member, a single circuit-controlling switch movable between circuit "on" and circuit "off" positions, a pivotally mounted switch-operating lever 15 movable between two positions corresponding to the respective circuit-controlling positions of said switch, means in relatively fixed relation to the driven member and operable to move said lever toward one position once during a complete cycle of the member, a second means for moving the lever toward the other of its said two positions in opposition to the first movement thereof once during a complete cycle of the member, said second means comprising an element 20 relatively fixed to the member and a complementary device adjustable relative to the element, said element being operable by the device at a variably predetermined point in the cycle of the member to establish a variably predetermined time interval between the respective movements of the lever.

JENS MORTON.
